UNITED STATES PATENT OFFICE.

JOHN J. DODGE, OF FRAMINGHAM, MASSACHUSETTS.

BANDOLIER CARTRIDGE-POUCH.

1,259,491.

Specification of Letters Patent. Patented Mar. 19, 1918.

Application filed July 21, 1915. Serial No. 41,182.

To all whom it may concern:

Be it known that I, JOHN J. DODGE, a British subject, residing in Framingham, in the county of Middlesex and State of Massachusetts, have invented new and useful Improvements in Bandolier Cartridge-Pouches.

My invention relates to the type of cartridge pouch known as the bandolier, which 10 consists in a general way of a broad belt or strap designed to be worn over the shoulder, and having small pouches attached at intervals as receptacles for ammunition. These pouches are small pockets preferably 15 of leather divided longitudinally into two compartments by a flap or tongue, and provided with a flap which may be folded over the top of the pocket and buttoned down onto the front. My invention relates more 20 particularly to the construction of these pouches or pockets, and to the method of forming the same and attaching them to the belt or strap.

The object of my invention is to provide 25 an improved construction and to provide a simple, quick, cheap, and effective method of forming and assembling such pockets, and of transferring and attaching them to the broad belt hereinbefore mentioned.

It has the further object of enabling these 30 pockets to be made up separately and transferred without danger of losing their shape or proper relation to each other to an assembling form receiving any desired number 35 of pockets, on which they may be attached to the belt.

It has the further object of so riveting 40 the pockets together that any force tending to pull them from the belt will cause a minimum stress in the leather.

I achieve these objects by building up the 45 pockets on a form, hereinafter described as the pocket form, using means to substantially fasten the pocket together so that it will retain its shape, and later transferring the built up pocket to an assembling form on which any desired number of pockets 50 may be placed and connected to the belt. The process is described in greater detail below.

In the accompanying drawings, in which 55 similar numerals or letters refer to like parts throughout the several views, Figure 1 represents the tongue of the pocket attached to the pocket form.

Fig. 2 shows the pocket blank with rivets

inserted being folded around the pocket form.

Fig. 3 shows the completed pocket before removal from the pocket form. 60

Fig. 4 shows a so-called five point assembling form for receiving five completed pockets for attachment to the belt, with a section thereof on the line X—X.

Fig. 5 shows the form of the pocket blank. 65

Fig. 6 the form of the blank for the tongue.

Fig. 7 a five point assembling form with four pockets attached, and illustrates the process of attaching them to the belt in different stages, and 70

Fig. 8 a perspective of a single pouch detached.

The method of forming the pockets and attaching them to the belt is as follows: The 75 pockets 21 and tongue blanks 22 (Figs. 5 and 6) are cut to shape, and the rivet holes punched in the locations shown. Rivets *a* and *b* are inserted in holes 1 and 2 of the tongue blank 22 and the large end of the 80 latter slipped under the clip spring 15 of the pocket form 16, the heads of the rivets *a* and *b* resting on the shelf 14. The small end of the tongue may be held back under the form by another similar clip spring (not 85 shown). Rivets *c* and *d* are now inserted in holes 3 and 4 of the pocket blank 21, and the blank folded around the form 16, passing the rivets *a* and *b* through holes 10 and 11. (Fig. 2). Next the flap of the pocket 90 blank 21 is folded over the top of the form, passing rivets *a*, *b*, *c*, and *d*, through holes, 5, 6, 7, and 8 respectively, and catching the button hole 9 on the pin 17. This pulls the pocket closely around the form, as shown 95 in Fig. 3. Burs or washers 18 are placed over the rivets *a*, *b*, *c*, and *d*, and forced down the tapered shank of the rivets firmly against the leather.

This operation serves to clamp the pocket 100 rigidly together, so that it may be removed from the pocket form and transferred to the assembling form without in any way affecting its shape or size.

Pockets are made up separately on the 105 pocket form 16 and then transferred to the assembling form 19; one pocket being placed on each point of the latter. In Fig. 7 the process of attaching the pockets to the belt is shown in successive steps. At the left is 110 shown an empty point of the form. Next to the right is a pocket 21 drawn onto a point

of the form, with the button hole 9 caught on the pin 20. Next in order comes a pocket over which the previously formed and punched belt 24 has been placed, with 5 the rivets *a*, *b*, *c*, and *d*, projecting through the holes in the belt. Finally are shown two pockets completely attached to the belt except for the upsetting of the rivets. Here is shown a second set of burs or washers 23 10 forced down over the shanks of the rivets to clamp the belt firmly to the pockets.

The first set of burs 18, which was forced over the shanks of the rivets *a*, *b*, *c*, and *d*, serves both to keep the pocket in shape during 15 the process of attaching it to the belt, and to help resist any force tending to pull the body of the pocket away from the flap 21. The second set of burs 23 serves to attach 20 the pocket firmly to the belt, and to resist any force tending to separate them. The use of these two sets of burs greatly increases the strength of the assembled bandolier, besides materially assisting in the construction.

It is, of course, not necessary that the 25 blanks or forms should be of the exact shape described, and many modifications may be made without departing from my invention.

Having therefore described my invention, 30 what I claim and desire to secure by Letters Patent is:

In a bandolier cartridge pouch; pockets formed by folding a suitably shaped blank, the same being secured in shape by rivets 35 passing through the back of the pockets and by burs or washers forced down over the shanks of the rivets; a flap or tongue dividing the pocket longitudinally into two compartments and secured on the inside of the 40 pocket by rivets; and a connection of the pockets to the shoulder strap or belt of the bandolier by passing the above mentioned rivets through holes in the belt and securing them on the other side by a second set of 45 burs or washers and the heading of the rivets.

JOHN J. DOIJDGE.
